UNITED STATES PATENT OFFICE

GEORGE BRAUN, OF ST. LOUIS, MISSOURI

SAND SEPARATOR AND BLENDER

Application filed March 31, 1930. Serial No. 440,184.

The object of my invention is to make a sand separator and blender. A further object is to make a device of the character described to be used principally for separating sand and blending molding sand as is used in foundries. When the sand is removed from the molds, it is usually deposited on the floor of the foundry. It is desirable to re-use this sand. In lying on the floor it becomes mingled with foreign matter, such as dirt, nails, etc., and due to the presence of moisture, lumps develop in the sand. These lumps must be crushed and broken up to the condition of sand and the foreign matter must be removed. My device finds particular application in removing this foreign matter and in reconditioning the sand. My device is usually mounted on a dolly or wheels so that it may be moved around in the foundry to different locations. The device is motor driven and is made of few and simple parts that lend themselves readily to multiple production and may be cheaply made, easily assembled and repaired. It is sufficiently light in weight to permit its facile movement in the foundry.

With these and other objects in view, my invention has relation to certain novel features of construction and arrangement of parts as will be hereinafter more fully described, pointed out in the claims and illustrated in the drawings, in which

Fig. 1 is a side elevation on one side of my device.

Fig. 2 is a side elevation on the opposite side of my device. In neither of these figures are the wheels for rolling the device above shown.

Fig. 3 is a plan view of my device.

Fig. 4 is a diagrammatic elevation showing my device as used on wheels.

Fig. 5 is a front elevation of my device.

Fig. 6 is a sectional elevation of my device taken on the line 6-6 of Fig. 5.

Fig. 7 is a fragmental sectional elevation of the sifter used in my device, together with its positioning elements. Fig. 7 is taken on the line 7-7 of Fig. 6.

Fig. 8 is an enlarged fragmental sectional elevation of a portion of my device showing the sifter reciprocating wheel.

Numeral 9 designates the casing of my device, which is composed of the side walls 10 and 11, the front wall 12 and the rear wall 13. The casing 9 may be made of wood or any suitable material. The rear wall 13 is off-set to form the platform 14, on which is positioned the motor 15. I have indicated an electric motor 15, which drives the mechanism of my device. Numeral 16 designates a truncated hopper secured to the top of the casing 9 as shown in the drawings. Numeral 17 designates an axle operatively secured to the bottom 18 of the casing 9. Numerals 20 designate wheels operatively secured to the axle 17 external to the casing 9. Numeral 21 designates a foot secured to the bottom 18 of the casing 9, for supporting the rear end of the casing 9 on the floor as shown in Fig. 4. In the front wall 12 is formed the opening 22, into which is fitted the spout 23, which is positioned as shown by the drawings having the inwardly extending inclined plane 24. Numeral 25 designates an axle passing through the side walls 10 and 11 and being journaled in the journal boxes 26 and 27, which are secured in the side walls 10 and 11. Numeral 28 designates a paddle wheel secured to the axle 25 between the side walls 10 and 11 and having the paddles 29. It will be seen that by a rotation of the axle 25 that the paddle wheel 28, will be rotated and that the paddles 29 will be rotated within the casing 9. The paddles 29 are of such length as not to come in contact with any of the walls of the casing in their rotation. The paddles 29 are all of the same length. Numerals 30 and 31 designate sprocket wheels keyed to one end of the axle 25 external to the side wall 10.

Numeral 32 designates an endless chain 90 which is in mesh with one of the sprocket wheels 31 and also in mesh with a sprocket wheel 33, which is keyed to the armature of the motor 15. By the structure thus far described, it will be seen that when the armature of the motor 15 is rotated that the paddle wheel 28 will be rotated. Numeral 34 designates an axle passing through the side walls 10 and 11 parallel and above the axle 25 and journaled in the side walls 10 and 11 100.

by means of the journal boxes 35 and 36. To the one external end of the axle 34 on the same side of the casing 9 as the external end of the axle 25, to which the sprocket wheels 30 and 31 are keyed, is keyed the sprocket wheel 37. Numeral 38 designates an endless chain in mesh with one of the sprocket wheels 31 and in mesh with the sprocket wheels 37. On the opposite end of the axle 34 external to the casing 9 is keyed the sifter reciprocating wheel 39. It will be seen that by the structure thus far described that when the armature of the motor 15 is rotated that not only the paddle wheel 28 will be rotated, but that the sifter reciprocating wheel 39 will also be rotated. On the axle 34 in the casing 9 is mounted the corrugated wheel 40. The diameter of the corrugated wheel 40 is such that it may be rotated with the axle 34 without coming in contact with the walls of the casing 9. The sifter reciprocating wheel 39 is rectangular in shape preferably square and has secured to each one of its sides the fingers 41. These fingers are slotted and are secured 25 to the sifter reciprocating wheel 39 by means of the screws 42, which pass through the slots in the fingers 41. By these means the projections of the fingers 41 over the edges of the reciprocating wheel may be adjusted. Numeral 43 designates the sifter which is rotatively secured to a brace 44, between the front wall 12 and the inset portion of the rear wall 13 above the wheel 34 and below the truncated hopper 16 by means of the pin 45, 30 which passes through the central brace 46 of the sifter 43. The sifter 43 is substantially rectangular in shape with rounded corners, having the frame 47 over which is secured the screen 48. The front wall 12 and the rear wall 13, that is inset, extend to the top of the sifter frame 47. The sifter frame is of such size that it may be reciprocated from side to side between the front wall 12 and the inset portion of the rear wall 13. To the one end 35 of the sifter frame 43 centrally positioned is located the arm 49, which arm is on the same side of the casing 9 as is the sifter reciprocating wheel 39. The arm 49 extends into the rotary path of the fingers 41 of the sifter reciprocating wheel 39. The fingers 41 of the sifter reciprocating wheel 39 are of such length that after they have moved the arm 49 to its limiting lateral position, they will 40 continue to rotate and disengage themselves from the arm 49. The resilience of the fingers 41 enables this to be done easily. In order to return the arm 49 to the position at the opposite end of its reciprocation, the spring 50 is provided, which is secured at one end to the casing 9 between the sifter reciprocating wheel 39 and the wall of the casing 9 and the other end is in contact with the arm 49. The spring 50 holds the arm 49 in its normal position on one end of its reciprocation. The sifter reciprocating wheel 39 as previously

indicated moves the arm 49 and the sifter 43 to the opposite end of its reciprocation.

The operation of my device is as follows:

Assuming that the motor 15 is operating and that hence the paddle wheel 28 is rotating and the corrugated wheel 40 is rotated and that the sifter reciprocating wheel 39 is rotating and that the sifter 43 is reciprocating within the limits previously described, the sand from the foundry floor is shoveled 75 on the truncated hopper 16, from which it falls into the sifter 43 where owing to the reciprocation of the sifter 43, the sand is permitted to fall through to the corrugated wheel 40. The foreign matter does not pass 80 through the sifter 43 and may be removed therefrom readily manually. The sand is further shaked and crushed on the corrugated wheel 40 and between it and the side walls of the casing 9 and then falls on to the 85 paddles 29 and the paddle wheel 28 where it is rotated and finally ejected through the spout 23 up the incline plane 24. The casing 9 is positioned at the most convenient angle for a proper ejection of the finished sand, by means of having the foot 21 of the proper height.

What I claim and mean to secure by Letters Patent is:

1. In a device of the character described 95 a casing, a horizontal sifter, said sifter positioned in said casing so as to permit its reciprocation, a corrugated wheel rotatively positioned beneath the screen in said casing in the path of the material to be sifted with 100 its periphery adjacent the casing walls, and means of reciprocating said sifter and rotating said corrugated wheel, a paddle wheel rotatively secured in said casing said paddle wheel being located beneath the corrugated wheel and in the path of the material, and means of rotating said paddle wheel, a motor, said motor operatively connected to said paddle wheel and said corrugated wheel and the means for reciprocating said sifter.

2. In a device of the character described 105 a casing, a horizontal sifter, said sifter positioned in said casing so as to permit its reciprocation, a corrugated wheel rotatively 110 positioned beneath the screen in said casing in the path of the material to be sifted with its periphery adjacent the casing walls, and means of reciprocating said sifter and rotating said corrugated wheel, a paddle wheel rotatively secured in said casing said paddle wheel being located beneath the corrugated wheel and in the path of the material, and means of rotating said paddle 115 wheel, a motor, said motor operatively connected to said paddle wheel and said corrugated wheel and the means for reciprocating said sifter, said means consisting of a sifter reciprocating wheel having fingers

formed thereon in the path of an arm secured to said sifter.

3. A device as specified in claim 1, in which there is an opening in the casing, and in which the paddle wheel is so positioned and rotated as to project the material from the opening.

In testimony whereof I affix my signature.

GEORGE BRAUN.
